UNITED STATES PATENT OFFICE.

DANIEL HIGHERGER FRANCIS, OF GRAND JUNCTION, COLORADO.

INTERNAL-COMBUSTION ENGINE.

1,229,602.

Specification of Letters Patent. Patented June 12, 1917.

Application filed December 27, 1915. Serial No. 68,771.

To all whom it may concern:

Be it known that I, DANIEL H. FRANCIS, a citizen of the United States, residing at Grand Junction, in the county of Mesa and 5 State of Colorado, have invented a new and useful Internal-Combustion Engine, of which the following is a specification.

The present invention appertains to internal combustion engines, and relates more 10 especially to valve mechanisms therefor.

It is the object of the invention to provide novel and improved valve structures for the cylinders of the explosion engine, for controlling the intake and exhaust ports, 15 the valves operating silently and effectively.

The invention resides in the use of conical or tapered valves controlling the intake and exhaust ports of the cylinders, and conical housings for said valves, novel means being 20 provided for connecting the valves for simultaneous rotation and to allow the valves to reciprocate slightly relative to one another when necessary. The invention also includes means whereby when the explosions 25 occur in the cylinders, auxiliary explosions occur in the valve housings adjacent the larger ends of the valves to hold said valves seated during the explosions, there being means for admitting carbureted air into the 30 auxiliary explosion chambers and for removing the burnt gases therefrom, simultaneously with the supply of carbureted air and exhaust of burnt gases from the cylinders. The invention also has other features as will appear when the mechanism 35 is more fully understood.

It is also within the scope of the invention to provide a valve mechanism which is comparatively simple and inexpensive in 40 construction, and which will be thoroughly practical, reliable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 45 within the scope of what is claimed without departing from the spirit of the invention.

The invention is illustrated in the accompanying drawings, wherein:

Figure 1 is a longitudinal median section 55 of the engine illustrating the improved valve mechanism, portions being shown in elevation.

Fig. 2 is a fragmental side elevation of 60 the engine.

Fig. 3 is a cross section taken on the line 3-3 of Fig. 1.

Fig. 4 is an enlarged sectional detail 65 through one valve, taken on the line 4-4 of Fig. 3.

Fig. 5 is a sectional view somewhat similar to Fig. 4 illustrating a lubricating means added to the valve structure.

The engine illustrated has the four cylinders 1 lying in a common plane, and attached to the crank casing 2 in which the crank shaft 3 is journaled, the cranks of said shaft being connected by the pitmen or connecting rods 4 with the pistons 5 which reciprocate in the cylinders as usual. 75

In carrying out the invention, the heads of the cylinders 1 are cast with spaced conical or tapered valve housings 6 which are in alignment or coaxial with their larger ends facing in the same direction, and the axes of the housings are arranged at right angles with the axes of the cylinders. Although the housings 6 are illustrated as being integral with the heads of the cylinders, they may, in practice, be separate castings, 85 and the housings 6 may be water jacketed or not, whichever is preferred.

The heads of the cylinders are each provided with a passage 7 establishing communication between the interiors of the cylinders and the larger ends of the housings 6, and the head of each cylinder is provided with the exhaust and intake ports 8 and 9, respectively, converging to the interior of the housing 6 from the cylinder, as seen in 95 Fig. 3. The housing 6 is provided diametrically opposite the respective ports 8 and 9, with ports 10 and 11, the ports 8, 9, 10 and 11 being arranged at the proper angles relative to one another about the circumference 100 of the housing 6.

At one side of the engine is the exhaust manifold 12 having its branches attached to the housings 6 in any suitable manner in

communication with the ports 10, while the intake manifold 13 is located at the opposite side of the engine and has its branches attached to the housings 6 in communication 5 with the ports 11. The intake manifold 13 is in communication with the carbureter 14 as usual.

The smaller ends of the housings 6 are open, while the larger ends thereof are 10 closed by removable caps 15 detachably engaged with the larger ends of the housings 6.

Mounted for rotation within each housing 6 is a conical or tapered valve 16 which seats snugly within the housing, and which is provided 15 with a diametrical passage 17 adapted to register with the ports 8, 9, 10 and 11, said ports and passage 17 being preferably elongated longitudinally of the housing and valve. The larger end of the valve 16 is 20 spaced from the respective cap 15 to provide an auxiliary combustion chamber 18 with which the passage 7 communicates. The larger end of the valve 16 has a pair of 25 diametrically opposite oblique passages 19 extending from the end face of the valve to the circumference or periphery thereof adjacent the respective ends of the passages 17, and the housing 6 is provided with passages 20 with which the passages 19 are adapted to 30 register, there being one of the passages or ports 20 for each of the ports 10 and 11, and said passages 20 being located adjacent and in communication with the respective ends of the said ports 10 and 11, as seen in Fig. 4.

In order to enable the valves to be rotated simultaneously, a stem 21 is secured rigidly 35 in any suitable manner to the smaller end of each valve coaxial therewith, and a washer 22 is disposed on each stem 21 and seats 40 against the smaller end of the respective housing 6. Coiled wire expansion springs 23 are disposed between the washers 22 and elements 24 secured to the stems 21, whereby 45 the springs 23 draw the valves 16 snugly within the housing 6 to hold said valves normally seated. All but one of the stems 21 extend 50 through the respective caps 15 of the companion housings 6, and the free ends of said stems fit slidably in sockets or recesses 55 26 with which the larger ends of the respective valves are provided. The ends of the 60 said stems 21 have keys or splines 27 engaging the respective valves 16, to constrain all of the valves to rotate in unison, although 65 the valves and stems can reciprocate or slide slightly relative to one another without breaking the connection therebetween. This 70 allows each valve to adjust itself relative to its housing. The caps 15 through which the 75 stems 21 project, are preferably provided with suitable packing means 25 to prevent leakage.

The remaining stem 21, seen at the left end in Fig. 1, is journaled through a bracket 28

attached to the respective end cylinder, and 65 has secured thereon a sprocket wheel 29 connected by an endless sprocket chain 30 with a sprocket wheel 31 keyed upon the crank shaft. The sprocket wheel 29 has a diameter four times as large as the sprocket wheel 31, 70 in order that the gear ratio between the crank shaft and valves will be 4 to 1. It is evident that the valves must be properly arranged according to the timing of the explosions, so that the valves are operated according 75 to the occurrences of the explosions in the respective cylinders, said explosions occurring in succession according to well established practice. It is evident that when the caps 15 are detached from the housings 6, 80 the valves can be readily moved from said housings, for purpose of cleaning, repair or replacement, and the parts can be readily assembled and properly positioned. Since the valves 16 are normally drawn snugly into 85 the housings under the influence of the springs 23, there will be no loose play of the valves within their housings, and the valves will rotate silently and snugly within their 90 housings. It is also to be noted that when the housings 6 contract and expand, due to changes in temperature, the valves can adjust themselves accordingly, since when the 95 housings expand, the valves will be drawn farther into the housings by the springs 23, and when the housings contract, they will force the valves backward against the tension of the springs 23. This provides for a snug fit of the valves at all times, to avoid 100 leakage and loose play.

Since the operation of all of the valves is the same, the operation of a single valve will suffice for all of them. Referring especially to Fig. 3, wherein the piston is illustrated as being at the end of the explosion stroke, the valve 16 rotating in the direction of the arrow, the passage 17 is just starting into communication with the exhaust ports 8 and 10. Now, as the piston 5 moves upwardly through its exhaust stroke, it will force the burnt gases through the port 8, passage 17 and port 10 into the exhaust manifold 12, the passage 17 moving past the ports 8 and 10 as the piston 5 moves through its exhaust stroke, and when the piston 5 reaches the end of its exhaust stroke, the passage 17 will come to a vertical position between the respective ports 8-9 and 10-11, to close the passage 17 110 momentarily. Then, when the piston 5 moves downwardly through its intake stroke, the passage 17 will move into communication with the intake ports 9 and 11, and as a result the carbureted air will be drawn from the manifold 13 through the port 11, passage 17 and port 9 into the cylinder. Now, when the piston again moves upward 115 through its compression stroke, the passage 120

17 is brought out of registration with the ports 9 and 11, moving toward a horizontal position, and as a result the carbureted air within the cylinder will be compressed. 5 While the passage 17 is still between the ports 9 and 10 and between the ports 8 and 11, the compressed charge is ignited by the spark plug (not shown) as usual, and the cylinder is forced through its explosion stroke to the position illustrated in Fig. 3. 10 The general action is the same as ordinary four-cycle engines, there being one explosion to every two revolutions of the crank shaft. The operation is then repeated as 15 before, excepting that the passage 17 is now in reversed position. It will therefore be noted that the valve 16 only makes one complete revolution for every four revolutions of the crank shaft. Upon the occurrence of one explosion in the cylinder, one side of the valve is exposed through the ports 8—9, while in the succeeding explosion the opposite side of the valve is exposed through the ports 8—9. The opposite sides 20 of the valve are thus alternately heated by the explosions, which will reduce the heating of the valve to a minimum.

Particular attention is directed to the fact that when the passage 17 is in communication with the intake port 11, the respective passage 19 will be in communication with the port 20 of the port 11, while the other passage 19 is closed, as seen in Fig. 4, by the lower portion of the housing 6. Thus, 25 the auxiliary explosion chamber 18 is in communication with the intake manifold, and the carbureted air will therefore also flow into the auxiliary combustion chamber 18 from the intake manifold 13 by way 30 of the respective port 20 and passage 19. When the explosion occurs in the cylinder, the carbureted air within the auxiliary combustion chamber 18 will also be ignited, and the force of the explosion within the chamber 18 will impinge against the larger end 35 of the valve 16 to hold said valve seated tightly within its housing during the explosion within the cylinder. This will prevent the explosion within the cylinder from 40 unseating the valve, it being noted that the explosion within the cylinder will extend through the ports 8—9 so as to impinge against the tapered or conical surface of the valve, which would, without the special 45 means provided to prevent it, force the valve from its seat toward the larger end of the housing 6. Now, when the passage 17 communicates with the exhaust port 10, as seen in Fig. 4, the respective passage 50 19 communicates with the port 20 of said port 10, and this allows the burnt gases to be exhausted from the chamber 18, the same as from the cylinder. The passage 7 between the chamber 18 and interior of the

cylinder facilitates the circulation of gas 65 into and out of the chamber 18. The auxiliary chambers 18 are of small proportions and utilize a minimum amount of fuel, the energy expended naturally assisting in the driving of the piston away from the head 70 of the cylinder, so that no energy is lost, since the valve 16 cannot yield in either direction by the pressures exerted thereagainst.

The valves may be lubricated by any suitable means. 75

The advantages and attributes of the invention will no doubt be obvious to those skilled in the art, without further comment being necessary. A salient feature, however, 80 of the invention resides in the fact that the operation of the engine can readily be reversed by using the manifold 12 as an intake manifold, and the manifold 13 as an exhaust manifold, the carburetor being transferred from one side to the other. 85

In Fig. 5, there is illustrated a lubricating device for the valve, and each valve and its housing may be provided with the lubricating device, as will be readily apparent. In 90 this case, the small end of the housing 6 has an inturned flange 32 through which the stem 21 slides, and the smaller end of the housing has packing means 22' embracing the stem 21 to prevent leakage. An oil or 95 lubricant chamber 33 is provided within the housing 6 between the smaller ends of the valve and housing, and the housing 6 has an inlet port 34 to which an oil or lubricant tube 35 is connected, said tube having a check 100 valve 36 for preventing the oil being forced back into the tube 35 from the chamber 33 by the pressure created within the chamber 33. Lubricant can thus be forced into the chamber 33 from the tube or pipe 35, and 105 this provides a cushion for the smaller end of the valve, to cushion the valve when it is forced into the housing by the explosion within the auxiliary chamber 18. This cushion 110 will avoid the jamming of the valve within the housing, and furthermore, the valve in being forced into the housing will compress the oil within the chamber 33, thus forcing a thin film of oil between the contacting surfaces of the valve and housing for purpose 115 of lubrication. It is preferable to provide that portion, designated 37, of the housing 6 between the ports 8 and 9 with a longitudinal oil groove 38 in which the oil can collect, for lubricating the valve, the groove 38 having 120 its upper end spaced suitably from the chamber 33, to prevent the direct flow of the lubricant from said chamber into said groove, but the groove 38 being at the lowest point 125 of the housing will receive the surplus lubricant to prevent the same flowing into the cylinder. The spring 23, in this case, bears against the smaller end of the housing, and

only exerts a pull sufficient to lightly draw the valve into place.

Having thus described the invention, what is claimed as new is:—

- 5 1. In an explosion engine, a cylinder having a conical housing, and a conical valve seated in said housing and having a passage for controlling the intake and exhaust, there being an auxiliary explosion chamber within said housing at the larger end of said valve, and said valve and housing having co-operating means independent of said passage for the intake and exhaust of gas to and from said chamber simultaneously with the cylinder.
- 10 2. In an explosion engine, a cylinder having a conical housing, a conical valve seated in said housing and having a passage for controlling the intake and exhaust, said housing having an auxiliary explosion chamber therein at the larger end of said valve, said cylinder having a passage establishing communication between it and said chamber, and said valve and housing having co-operating means independent of said passage for the intake and exhaust of gas to and from said chamber simultaneously with the cylinder.
- 15 3. In an explosion engine, a cylinder having a conical housing, said housing having intake and exhaust ports, there being means of communication between said housing and cylinder, a conical valve seated in said housing and having means for establishing communication between said ports and first mentioned means, there being an auxiliary explosion chamber in said housing at the larger end of said valve, and said valve having means independent of the aforesaid means of said valve for establishing communication between said ports and chamber simultaneously when said ports are brought into communication with the cylinder.
- 20 4. In an explosion engine, a cylinder having a conical housing, said housing having intake and exhaust ports, there being means of communication between said housing and cylinder, a conical valve seated in said housing and having means for establishing communication between said ports and first mentioned means, there being an auxiliary explosion chamber in said housing at the larger end of said valve, and said valve having independent means for establishing communication between said ports and chamber simultaneously when said ports are brought into communication with the cylinder, the cylinder having a passage establishing communication between it and said chamber.
- 25 5. In an explosion engine, a cylinder having a conical housing, said housing having intake and exhaust ports, said cylinder having intake and exhaust ports establishing communication between it and said housing,

a rotatable conical valve seated in said housing and having a passage to establish communication between the intake and exhaust ports alternately, there being an auxiliary explosion chamber within the housing at the larger end of said valve, said housing having auxiliary intake and exhaust ports in communication with its first mentioned intake and exhaust ports, and the larger end of the valve having passages communicating with said chamber and adapted to register with the auxiliary ports to establish communication between said chamber and first mentioned ports when said first mentioned ports are brought into communication with the cylinder.

6. In an explosion engine, a cylinder having a conical housing, said housing having intake and exhaust ports, said cylinder having intake and exhaust ports establishing communication between it and said housing, a rotatable conical valve seated in said housing and having a passage to establish communication between the intake and exhaust ports alternately, there being an auxiliary explosion chamber within the housing at the larger end of the said valve, said housing having auxiliary intake and exhaust ports in communication with said first mentioned intake and exhaust ports, and the larger end of the valve having passages communicating with said chamber and adapted to register with the auxiliary ports to establish communication between said chamber and first mentioned ports when said first mentioned ports are brought into communication with the cylinder, the cylinder having a passage establishing communication between it and said chamber.

7. In an explosion engine, a plurality of cylinders having spaced alining conical housings, rotary conical valves seated in said housings, and means connecting said valves for rotating them simultaneously.

8. In an explosion engine, a plurality of cylinders having spaced alining conical housings arranged in the same position, caps closing the larger ends of said housings, rotatable conical controlling valves seated in said housings and having independent coaxial stems projecting through said caps and slidably engaging the companion valves.

9. In an explosion engine, a plurality of cylinders having spaced alining conical housings arranged in the same position, caps closing the larger ends of said housings, rotatable conical controlling valves seated in said housings, the smaller ends of said valves having independent coaxial stems projecting through the respective caps and slidably engaging the larger ends of the companion valves, and spring means between said stems and the smaller ends of the housings for yieldably seating the valves.

10. In an explosion engine, a cylinder having a conical housing, a conical controlling valve seated in said housing, there being an explosion chamber between the larger 5 ends of the valve and housing, and a lubricant chamber between the smaller ends of said valve and housing, and means for supplying lubricant to said lubricant chamber, one of the contacting surfaces of the valve 10 and housing having lubricant holding means to receive lubricant forced between them. 11. In an explosion engine, a cylinder having a conical housing, a conical controlling valve seated in said housing, there being an 15 explosion chamber between the larger ends of the valve and housing, and a lubricant chamber between the smaller ends of said valve and housing, the lower portion of said housing having a lubricant groove spaced from the lubricant chamber and adapted to receive lubricant forced between the valve and housing. 20 12. In an explosion engine, a cylinder having a conical housing, a rotatable conical controlling valve seated in said housing, there being an explosion chamber between the larger ends of said valve and housing, and a lubricant chamber between the smaller ends of said valve and housing, and check 25 valved means for delivering lubricant into the lubricant chamber, one of the contacting surfaces of the valve and housings having lubricant holding means spaced from the lubricant chamber to receive lubricant forced between the valve and the housing. 30 35 13. In an explosion engine, a cylinder having a conical housing, a rotatable conical controlling valve seated in said housing and having a stem projecting from its smaller end through the smaller end of the housing, a spring between said stem and smaller end of the housing to seat the valve within the housing, there being an explosion chamber between the larger ends of the valve and housing, and a lubricant chamber between the smaller ends of the valve and housing, the lower portion of the housing having a longitudinal lubricant groove spaced from the lubricant chamber, and check valved means for supplying lubricant into the lubricant chamber. 40 45 50

In testimony that I claim the foregoing as my own, I have hereto affixed my signature in the presence of two witnesses.

DANIEL HIGHBERGER FRANCIS.
